ATTORNEY

WITNESS:

UNITED STATES PATENT OFFICE.

JOHN M. LAIRD, OF HUNTINGDON, PENNSYLVANIA.

RADIATOR SHELL.

Application filed September 20, 1922. Serial No. 589,417.

To all whom it may concern:

Be it known that I, JOHN M. LAIRD, a citizen of the United States, residing at Huntingdon, in the county of Huntingdon and State of Pennsylvania, have invented new and useful Improvements in Radiator Shells, of which the following is a specification.

This invention relates to radiator shells for use on automobiles and has for its object the provision of a shell of novel construction whereby air will be permitted to enter and impinge against the front of the upper tank of the radiator for the purpose of effecting cooling thereof.

An important object is the provision of a shell of this character which is designed to be used in connection with already existing radiators and to replace the ordinary shell without necessitating any changes in the construction of the radiator to which it is applied.

An additional object is the provision of a device of this character which will be simple and inexpensive in manufacture, easy to install, efficient and durable in use and a general improvement in the art.

With the above and other objects and advantages in view the invention consists in the details of construction to be herein-after more fully described and claimed and illustrated in the accompanying drawings, in which:

Figure 1 is a front elevation of the shell, Figure 2 is a vertical section therethrough showing it associated with a radiator and

Figure 3 is a cross section on the line 3—3 looking up.

Referring more particularly to the drawings the letter A designates, conventionally, an ordinary radiator with which my device may be associated. In carrying out my invention I provide a shell 10 which is constructed of sheet metal in the usual manner and which is of the customary shape depending upon the make of automobile or radiator upon which the shell is to be used. At opposite sides the shell carries the usual lateral extensions 11 by means of which it may be mounted upon

the frame of the vehicle, these extensions being provided with holes 12 for the passage of the studs provided for holding the radiator and shell therefor. The upper portion of the shell is formed as a plate 13 and instead of being solid as is the usual construction this plate is cut and stamped to provide a plurality of louvers 14, that is openings or slits having the metal outstruck to overhang them. The lower edge of this plate 13 is extended rearwardly and is formed with a plurality of openings 15 which communicate with the space between the plate 13 of the shell and the front wall 65 of the upper tank of the radiator.

In the use of my device it will be seen that air will not only enter the openings 15 but will also enter the louvers and thus impinge against the radiator tank and effect cooling thereof.

From the foregoing description and a study of the drawings it will be apparent that I have thus provided a simply constructed and consequently inexpensive radiator shell which may be used to replace those of the ordinary type and which will be highly advantageous in insuring proper cooling of the upper tank of a radiator, it being well known that this upper tank is 70 naturally the hottest point in the entire water system of an automobile engine.

While I have shown and described the preferred embodiment of the invention it is of course to be understood that I reserve 85 the right to make such changes in the form, construction and arrangement of parts as will not depart from the spirit of the invention or the scope of the subjoined claim.

Having thus described my invention I 90 claim:

A radiator shell having its upper portion of a plate like nature and provided with louvers permitting ingress of air to the front wall of the radiator tank, the lower 95 edge of said plate being extended rearwardly and formed with a series of openings establishing communication between the atmosphere and the space between the front plate of the shell and the upper tank 100 of the radiator to which it is applied.

JOHN M. LAIRD.
